UNITED STATES PATENT OFFICE

147,316

DESIGN FOR A RADIO CABINET
OR THE LIKE

Robert E. Bingman, Detroit, Mich., assignor to
Bendix Aviation Corporation, South Bend,
Ind., a corporation of Delaware

Application February 14, 1946, Serial No. 126,548

Term of patent 3½ years

(Cl. D56—4)

To all whom it may concern:

Be it known that I, Robert E. Bingman, a citizen of the United States, residing in Detroit, in the county of Wayne and State of Michigan, have invented a new, original, and ornamental Design for a Radio Cabinet or the like, of which the following is a specification, reference being had to the accompanying drawings, forming a part thereof.

In the drawings:

Figure 1 is a front elevational view of a radio cabinet, or the like, showing my new design;

Figure 2 is a rear elevational view thereof;

Figure 3 is a top plan view thereof, and;

Figure 4 is a side elevational view thereof.

What is claimed is:

The ornamental design for a radio cabinet or the like, as shown.

ROBERT E. BINGMAN.
